CONDUCTOR CLAMP

Kent A. Hawley, Baltimore, Md., assignor to
Locke Insulator Corporation, Baltimore, Md., a
corporation of Maryland

Application June 17, 1927, Serial No. 199,512

2 Claims. (Cl. 248—31)

The invention relates to clamps such as are used for the suspension of the conductors of transmission lines, for securing a ground conductor, and for other purposes.

5 In transmission line practice it is customary to provide conductor clamps which are pivoted with respect to the insulator string from which the conductor is suspended. The pivot point of the clamp is generally several inches from the 10 suspension device and the result is that when the clamp moves in accordance with vibrations of the conductor the clamp must move longitudinally as well as pivotally. As such clamps are necessarily of fairly heavy construction so as to withstand 15 service strains they have considerable inertia and will not follow the vibrations of the conductor. It consequently occurs that the conductor may bend more or less sharply at the edge of the clamp, resulting in crystallization and even- 20 tual breaking of the conductor strands. It therefore becomes a matter of importance to reduce the inertia so that the clamp may respond instantly and accurately to the vibrations which are 25 always present in the transmission line.

It is with the above facts in view that I have 30 designed the present invention which has for its principal object the provision of a clamp so constructed and having such a pivotal mounting that it will offer the minimum resistance to the conductor vibrations, that is to say the inertia will be reduced so that the clamp may follow the vibrations without lagging and causing bending strains in the conductor to be set up.

The object of the invention, more specifically 35 stated, is to provide a clamp pivoted on an axis transverse to and intersecting the longitudinal axis of the conductor whereby necessary movement in a vertical plane will be permitted without changing the location of the center of mass 40 of the clamp and without any change in the position of the supporting parts above it.

Still another object of the invention is to provide a clamp of such construction that there will be a rolling rather than a sliding contact at the 45 pivot so as to facilitate oscillation.

A further object is to provide a clamp having a novel arrangement of pivot means and a novel mounting therefor on the suspension means whereby assembly, or disassembly, may be effected quickly and easily.

An additional object is to provide a clamp of this character which will be simple and inexpensive to manufacture, positive in action, efficient and durable in service, and a general improvement in the art.

To the attainment of the foregoing and other objects and advantages, the invention preferably consists in the details of construction and the arrangement and combination of parts to be hereinafter more fully described and claimed, and illustrated in the accompanying drawing in which:

Figure 1 is a side elevation of a clamp constructed in accordance with the preferred form of the invention.

Figure 2 is a top plan view thereof with the 10 suspension links in section.

Figure 3 is an end view.

Figure 4 is a detail cross section taken on the line 4—4 of Figure 1.

Referring more particularly to the drawing, I 15 have shown the clamp as comprising a lower clamping member indicated generally at 1, this member being of suitable size and weight depending upon the size of the conductor to be held. This member may conveniently be formed 20 as a casting though there is no particular limitation in this respect. In detail, the member 1 comprises an elongated body channel shaped in cross section or formed with a longitudinally extending groove 2 for the reception and accom- 25 modation of the conductor 3, the central portion of the bottom of the groove being substantially straight and constituting a seat 4 conformingly engaged by the conductor. The ends of the member 1 are preferably curved downwardly as clearly shown so that the conductor will be out of contact with the ends. At opposite sides, the member 1 is shown as provided 30 with a plurality of laterally extending lugs or ears 5 formed with holes 6 for a purpose to be 35 described. In order to rigidify the structure the underside of the member 1 is preferably provided with a central longitudinally extending rib 7 intersecting a transverse rib 8. Clearly, these 40 ribs will act as trusses for reinforcing the clamp at the portion subject to the greatest strain. However, many variations in the number and arrangement of reinforcement elements are possible.

The clamp further includes an upper clamping member 9 which may be of substantially the same length as the member 1 and of a size to be received within the groove 2 for clamping engagement with the conductor 3. The member 9 may conveniently be formed as a casting but regardless of this detail is preferably provided inwardly of its ends with pairs of spaced ribs 10 defining seats 11 for securing bolts 12 which might conceivably be of the J-type but which are here represented as U-shaped with the arms 55

thereof passing through the holes 6 in the members 5 and equipped with nuts 13. By providing the seats 11 it is clear that when the bolts are in place it will be impossible for the clamping member 9 to shift longitudinally with respect to the member 1.

Between the inner ones of the pairs of ribs 10 the member 9 is preferably provided with a central longitudinally extending stiffening rib 14 for reinforcing purposes at the portion of greatest strain. Beyond the outermost ribs 10 the end portions of the member 9 are preferably curved upwardly away from the conductor so as to avoid contact therewith even though violent vibration of the conductor might occur from any cause. The member 9 is preferably concavo-convex in cross section or at least formed with a grooved underside 15 so as to conform substantially to the conductor clamped between the members 1 and 9. The outward opposite curving of the ends of the members 1 and 9 gives them a bell mouthed shape as this has been recognized as being the most advisable arrangement to avoid the bringing of bending strains on the conductor which would result if the conductor were clamped tightly at these end portions.

The numeral 16 designates suspension links adapted to be connected in any suitable or preferred manner with a suspension device indicated by dot and dash lines 17. The principal feature of the invention is the particular mounting of the clamp with respect to the links 16. Preferably, the lower clamping member 1 is formed with trunnions 18 which project outwardly from opposite sides between the lugs or ears 5, reinforcing bosses 19 being provided at the base of the trunnions or at their juncture with the member 1. These trunnions are represented as of cylindrical form and they preferably terminate in heads 20 which are elongated downwardly so as to project beyond the lower surface of the trunnions. The links 16 are formed with elongated openings 21 receiving the trunnions and of preferably slightly greater width than the diameter thereof so as to permit the trunnions to have more or less of a rolling action rather than a sliding action when pivoting of the clamp occurs. The openings 21 must be at least slightly greater size than the heads 20 so as to permit the links to be engaged upon the trunnions. When assembly is effected it is of course apparent that the heads 20 will project beyond and overlie the material at the lower ends of the openings so that disconnection of the links from the clamp by lateral movement with respect thereto will be prevented. While it is not essential it may be preferable to provide cotter pins 22 which extend through the heads 20 for assisting the holding action.

The above described clamp is assembled in an obvious manner and it will be apparent that in

service the clamping members themselves may turn as a unit with the trunnions as a pivot mounting, the axis of rotation extending substantially through the center line of the conductor at right angles thereto. There is consequently no change in the position of the center of mass and the objectionable inertia effects in ordinary structures are thus avoided. In other words the clamp may accommodate itself to vibrations in the conductor so as to avoid the bringing of any bending strains whatsoever thereon, danger of crystallization and consequent breakage being eliminated.

From the foregoing description and a study of the drawing it will be apparent that I have thus provided a simply constructed and inexpensive clamp which may be quickly and easily assembled or disassembled and which will in every way possess the advantages and perform the functions above outlined. Experience has demonstrated that a conductor mounted by means of such clamps is free from bending strains and will therefore have a long life.

While I have shown and described preferred embodiments of the invention, it should be understood that the disclosure is merely an exemplification of the principles involved as the right is reserved to make all such changes in the details of construction as will widen the field of utility and increase the adaptability of the device provided such changes constitute no departure from the spirit of the invention or the scope of the claims hereunto appended.

Having thus described the invention, I claim:

1. In a clamping device of the character described, a pair of clamping members disposable against opposite sides of a conductor, means for maintaining the clamping members in clamping relation upon the conductor, trunnions projecting laterally from one clamping member, and suspension links pivotally receiving said trunnions, the trunnions having elongated heads thereon, and the links having correspondingly elongated openings for the passage of the heads, whereby after assembly the heads will overlap the openings for preventing withdrawal.

2. In a clamping device of the character described, a pair of clamping members disposable against opposite sides of a conductor, means for maintaining the clamping members in clamping relation upon the conductor, trunnions projecting laterally from one clamping member, and suspension links pivotally receiving said trunnions, the trunnions having elongated heads thereon, and the links having correspondingly elongated openings for the passage of the heads, the openings being of slightly greater width than the diameter of the trunnions to permit a rolling movement.

KENT A. HAWLEY.
